UNITED STATES PATENT OFFICE.

FRANK G. WOODRUFF, OF LOCKPORT, NEW YORK, ASSIGNOR TO OLIVER BROTHERS COMPANY, OF LOCKPORT, NEW YORK.

DESIGN FOR A BEDSTEAD END FRAME.

SPECIFICATION forming part of Design No. 36,606, dated October 27, 1903.

Application filed August 25, 1903. Serial No. 170,761. Term of patent 3½ years.

To all whom it may concern:

Be it known that I, FRANK G. WOODRUFF, a citizen of the United States, residing at Lockport, in the county of Niagara and State 5 of New York, have invented a new, original, and ornamental Design for Bedstead End Frames, of which the following is a specification, reference being had to the accompanying drawings, forming a part thereof.

Figure 1 of the drawings is a front elevation of an end frame of a bedstead disclosing the design. Fig. 2 is a perspective view thereof.

What I claim as new, and desire to secure by Letters Patent, is—

The ornamental design for a bedstead end frame, as herein shown.

Witness my hand this 14th day of August, 1903.

FRANK G. WOODRUFF.
